Rochelle, N.Y., assignors to Electronic Devices, Inc.,
Brooklyn, N.Y., a corporation of Delaware

Application November 17, 1958, Serial No. 53,389

Term of patent 7 years

(Cl. D26—15)

Figure 1 is a perspective view of a rectifier showing the new design;

Figure 2 is a front elevational view;

Figure 3 is a top plan view thereof;

Figure 4 is a bottom plan view thereof;

Figure 5 is a side elevational view, the opposite side being substantially a mirror image thereof; and

Figure 6 is a rear elevational view thereof.

Portions of the drawing figures are stippled to indicate contrast in appearance.

We claim:

The ornamental design for a rectifier, substantially as shown and described.
